(57) **CLAIM**

The ornamental design for a collapsible decoy support, as shown and described.

DESCRIPTION

FIG. 1 is a perspective view of a first embodiment thereof, with dotted lines indicating a decoy head and stake and dotted-and-dashed lines indicating a decoy body;

FIG. 2 is a perspective view of the first embodiment;

FIG. 3 is a front view thereof;

FIG. 4 is a rear view thereof;

FIG. 5 is an end view thereof, as taken from the right side in FIG. 4;

FIG. 6 is an end view thereof, as taken from the left side in FIG. 4;

FIG. 7 is a top view thereof;

FIG. 8 is a bottom view thereof;

FIG. 9 is a perspective view of a second embodiment thereof, with dotted lines indicating a decoy head and stake and dotted-and-dashed lines indicating a decoy body;

FIG. 10 is a perspective view of the second embodiment;

FIG. 11 is a front view thereof;

FIG. 12 is a rear view thereof;

FIG. 13 is an end view thereof, as taken from the right side in FIG. 12;

FIG. 14 is an end view thereof, as taken from the left side in FIG. 12;

FIG. 15 is a top view thereof; and,

FIG. 16 is a bottom view thereof.

The dotted and dotted-and-dashed lines depict environmental structure and form no part of the claimed design.

1 Claim, 8 Drawing Sheets
